UNITED STATES PATENT OFFICE.

THOMAS G. TAYLOR, OF LEAKSVILLE, NORTH CAROLINA.

CURTAIN-HOLDER FOR BUGGIES.

1,172,179.

Specification of Letters Patent. Patented Feb. 15, 1916.

Application filed February 17, 1915. Serial No. 8,834.

To all whom it may concern:

Be it known that I, THOMAS G. TAYLOR, a citizen of the United States, residing at Leaksville, in the county of Rockingham and State of North Carolina, have invented new and useful Improvements in Curtain-Holders for Buggies, of which the following is a specification.

The present invention relates to an attachment for the dash board of vehicles, to protect that portion of the lap robe that extends over the dash board from wear or other injury by the friction caused by the constant movement of the driving reins thereover.

Another object of the invention is the provision of a device of this character which is simple in construction, cheap to manufacture, and one capable of adjustment to accommodate dash boards of varying widths.

In the drawing forming part of this application like numerals of reference indicate similar parts in the several views and in which:

25 Figure 1 is a perspective view showing the application of the device. Fig. 2 is an elevation partly in section. Fig. 3 is a transverse sectional view taken on line a—a of Fig. 2. Fig. 4 is a detail sectional view of a modified form of the invention.

In the preferred embodiment of the invention the device comprises a hollow rod including the telescopic sections 5 and 6 respectively, each of which has associated therewith a spring clamp 7 adapted to embrace the upper edge of the dash board 8 after the lap robe 9 has been spread thereover. Each of the clamps 7 is constructed from a single length of resilient metal, bent 40 upon itself to provide an intermediate loop portion 10 and spreadable legs 11. The loop 10 in this embodiment of the invention is disposed within the rod and engaged against the inner surface thereof, while the legs 11 project downwardly through a suitable slot 12 as shown. Obviously when the device is in operative position as illustrated in Fig. 1, the rod rests upon the upper edge of the dash board above that portion of the lap robe extended thereover, so that the driving reins instead of coming in contact with the lap robe, will move over the rod, thus protecting the lap robe from wear or other in-

jury resultant from constant friction between these parts. Now in order to space 55 the rod a slight distance from the lap robe, I employ rubber buffers 13, one being disposed and suitably secured between the legs 11 of each clamp. The buffers in this instance however are shown to be provided 60 with a cylindrical portion 14 that is secured within the loop portion 10 of the clamp, while the body portion 15 projects between the legs and is coextensive in width therewith.

A modified form of the invention is illustrated in Fig. 4 wherein the loop portion 16 of the clamp encircles the rod, the latter being cut away to receive the loop so that the latter will lie flush with the outer surface 70 of the rod, and is secured thereto by means of fastening elements 17. The under side of the rod is formed with an elongated longitudinally disposed recess 18 for the reception of the buffer 19, the latter having a 75 portion depending between the legs 20. In addition to protecting the lap robe in the manner hereinabove described, the attachment in place serves to retain the lap robe in position upon the dash board of the vehicle.

It is believed that from the foregoing description the nature and advantages of the invention will be thoroughly understood without requiring a more extended explanation and therefore the same has been omitted. However I desire to have it understood that what I have shown and described is merely illustrative, and that various changes in the construction and arrangement of parts may be resorted to when desired as fall within the scope of the appended claim.

What I claim is:—

In a device of the class described, comprising a rod, resilient clamps depending therefrom and having spreadable legs, and a buffer arranged between the legs of each clamp.

In testimony whereof I affix my signature 100 in presence of two witnesses.

THOMAS G. TAYLOR.
